TONGS FOR PULLING WEEDS AND THE LIKE

Katsumi Harano, 5609 Bowcraft, Los Angeles, Calif.

Filed Oct. 16, 1961, Ser. No. 67,079

Term of patent 14 years

(Cl. D35—2)

Fig. 1.

Fig. 2.

Fig. 3.

Fig. 4.

Fig. 5.

Fig. 6.

Fig. 7.

FIG. 1 is a perspective view of tongs for pulling weeds or the like showing my new design;

FIG. 2 is a side elevation of one side thereof;

FIG. 3 is an elevation of the opposite side thereof;

FIG. 4 is a top plan view thereof;

FIG. 5 is a bottom plan view thereof;

FIG. 6 is a front elevation thereof; and,

FIG. 7 is a rear elevation thereof.

I claim:

The ornamental design for tongs for pulling weeds or the like, substantially as shown.
